(57) **CLAIM**

The ornamental design for a pneumatic tyre, as shown and described.

DESCRIPTION

1.1-front view of a pneumatic tyre showing our design;

1.2-back view thereof;

1.3-left view thereof;

1.4-right view thereof;

1.5-top view thereof;

1.6-bottom view thereof; and

1.7-perspective view thereof.

The broken lines shown in the drawings depict portions of the pneumatic tyre that form no part of the claimed design.
